GAS ODOR READING METER

Harold W. Darr, Minneapolis, Minn., assignor to United Petroleum Gas Company, Minneapolis, Minn., a corporation of Minnesota

Application August 20, 1953, Serial No. 26,531

Term of patent 14 years

(Cl. D52—1)

Fig. 1

Fig. 2

Fig. 3

Fig. 4

Fig. 1 is a view in perspective of a gas odor reading meter, showing my new design;

Fig. 2 is an end elevation as seen from the right to the left with respect to Fig. 1;

Fig. 3 is a view in side elevation of the side opposite to that shown in Fig. 1; and

Fig. 4 is a view in plan, the handle of the device being swung 90° from its position of Figs. 1 to 3 inclusive.

I claim:

The ornamental design for a gas odor reading meter, as shown.
